UNITED STATES PATENT OFFICE.

STANISLAUS BERENS, OF LAGRANGE, ILLINOIS, ASSIGNOR OF ONE-HALF TO
FRANK J. LODESKI, OF CHICAGO, ILLINOIS.

HYDROCARBON-BURNER.

SPECIFICATION forming part of Letters Patent No. 710,410, dated October 7, 1902.

Application filed April 14, 1902. Serial No. 102,789. (No model.)

To all whom it may concern:

Be it known that I, STANISLAUS BERENS, a citizen of the United States, residing at La-
5 grange, in the county of Cook and State of Illinois, have invented certain new and use-
ful Improvements in Hydrocarbon-Burners, of which the following is a specification.

This invention relates to improvements in
10 that class of burners employed for burning
hydrocarbon oils or liquid fuel, and while it
is more especially intended to be used for
heating the steam generators or boilers of
automobiles, yet it is applicable for assaying-
15 furnaces, retorts, and for other heating pur-
poses; and it consists in certain peculiarities
of the construction, novel combination, and
arrangement of the various parts of the ap-
paratus, all substantially as will hereinafter
20 more fully appear and be set forth in the
claims.

The principal object of the invention is to
provide a burner for hydrocarbon oils of sim-
25 ple and economical construction in which the
oil is vaporized by the heat of its own com-
bustion.

Another object is to so construct the appa-
ratus that its parts will not become over-
heated, thereby insuring greater durability
and preventing the burner burning back.

30 Still another object is to afford a burner so
constructed that the heat will be uniformly
distributed throughout its entire area.

Other objects and advantages of the in-
vention will be disclosed in the subjoined de-
35 scription and explanation.

In order to enable others skilled in the art
to which my invention pertains to make and
use the same, I will now proceed to describe
it, referring to the accompanying drawings,
40 in which—

Figure 1 is a front view in elevation of a
burner embodying my invention, showing a
portion of the oil-supply pipe and a part of
the water and steam pipes connected thereto.

45 Fig. 2 is a plan view thereof. Fig. 3 is a view,
partly in section and partly in elevation, of
the inner portion of the initial generator or
pilot-light. Fig. 4 is a sectional view taken
50 on line 4 4 of Fig. 3 looking in the direction
indicated by the arrows, showing the outer
portion of the initial generator in position on
the inner part. Fig. 5 is a fragmental plan

view of a portion of the burner, showing the
manner of securing the heat-distributing bars
thereof together. Fig. 6 is a face view of one 55
of said bars; and Fig. 7 is a sectional view
taken on line 7 7 of Fig. 1 looking in the di-
rection indicated by the arrows, showing two
of the valves for controlling the flow of oil.

Similar letters refer to like parts through- 60
out the different views of the drawings.

A represents the main casing of the burner,
which is made of any suitable size and form,
but preferably rectangular or box-like in
shape, as shown in the drawings. This cas- 65
ing has its bottom closed and is provided on
the outer surface of its wall with a number
of lugs a to receive the ends of bolts a', which
pass through openings in lugs a² on the outer
surface of the vaporizer or gas-generating 70
frame B, which is located on the upper per-
imeter of the casing A, as is clearly shown in
Fig. 1 of the drawings, and is held in said
position by means of the bolts a', as is appa- 75
rent. The frame B is provided with a con-
tinuous opening b, access to which for clean-
ing the same may be had through tubular ex-
tensions b' at its corners, which extensions
are closed by means of screw-plugs b², located 80
in each of said extensions. Secured to one of
the front corners of the vaporizer or frame B
and communicating with the opening or chan-
nel b thereof is an oil-supply pipe C, which
may be connected at its other end to a source 85
of oil-supply. (Not shown.) Located in the
upper portion of the casing A and just below
the frame B are a series of parallel bars D,
which preferably extend from the rear to the
front of the burner, as shown. These bars 90
are each provided with a series of openings
d for the reception of the water-pipes E, which
are connected together at their ends outside
of the casing A by means of coupling-pieces
e, thus forming a continuous circulation for 95
the water. One of the pipes E communicates
with the water-reservoir and the other with
the boiler, both of which are not shown. The
bars D are also provided with openings d' for
the reception of securing-bolts d², which pass 100
through the sides of the casing A and are held
in place by means of nuts d³ on their outer ends.
The bars D are held a slight distance apart by
means of washers d⁴, located on the rods d² and between the bars D, as is

clearly shown in Figs. 2 and 5 of the drawings.

The front central portion of the casing A is furnished with a horizontal tubular extension F, which communicates with the interior of the casing below the vapor or gas distributor G, which is located horizontally within the casing A and extends from its front to near its rear part and is provided with a series of 10 openings g for the escape of the gas or vapor. The vaporizer or frame B is provided in its front portion, near the oil-supply pipe C, with an outlet opening and pipe C', which communicates with a hollow boss h on the initial 15 generator or pilot-light frame H, which frame is provided with openings h', access to which may be had for cleaning the same through extensions h² at its corners, which extensions are closed by screw-plugs h³, as shown in Fig. 20 20 of the drawings. The hollow boss h communicates with the openings h' through an opening h⁴, and the openings h' communicate with another hollow boss h⁵ on the frame H through an opening h⁶, and the last-named 25 boss is connected to a pipe h⁷, which communicates at its outer end with a pipe h⁸, which is provided with a valve-chamber h⁹ and a needle-valve h¹⁰ of the ordinary construction, as is clearly shown in Fig. 7 of the 30 drawings. The pipe h⁸ is provided with a downwardly-extending pipe g', which is provided in its lower portion with a needle-valve 35 g² of the same construction as that shown in Fig. 7 of the drawings. Below the needle-valve g² the pipe g' is provided with a cup g³, which extends under the valve h⁹, as well as the valve g², and is employed to hold oil or alcohol to be ignited for starting the generation of vapor or gas from the oil in the 40 pipe h⁸ and in said valves. Secured to the pipe h⁸ at its end adjacent to the pipe g' is the oil-regulator K, which communicates with a source of steam-supply (not shown) through a pipe k and which regulator may be of the 45 ordinary or any preferred construction and has a rod i with a piston or valve i' on its end to close the end of the pipe h⁸, adjacent to the pipe g', thereby regulating the flow of oil to the valve in the lower portion thereof. 50 The initial generator or frame H is located in a casing comprising two box-like sections L and L', which are secured together by means of bolts m, located in suitable lugs on the ends of said sections. Between the sections 55 L and L' is located a perforated partition m', a portion of which is shown in Fig. 3 of the drawings. The section L is provided with an opening n, which is located above the frame B of the burner and through which the gas or vapor from the burner may be ignited. The section L' of the pilot-light casing is provided with a tubular extension N, which is located near the opening in the valve-chamber h⁹ and receives the gas or vapor therefrom, where it will be mixed with the air and distributed through the perforations of the 60 partition m' of the pilot-light casing. The 65

valve g² is located near and directly in front of the tubular extension F in the front of the burner-casing and discharges into the same, 70 thus forcing the gas or vapor and air or steam through said extension and into the shell-like distributor G, from which it will pass through the openings g thereof out under the bars D, which will further serve to distribute the gas 75 or vapor.

From the foregoing and by reference to the drawings it will be seen and clearly understood that oil will be supplied to the generator B through the pipe C and from said generator through the pipe C' to the initial generator-frame H, from which the pipe h⁸ will be supplied. By placing a quantity of oil or other inflammable substance in the cup g³ and igniting the same it is apparent that the 85 oil contained in the pipes h⁸ and g' will be converted into vapor or gas and discharged through the respective valves of said pipes into the extensions F and N and through the former into the burner, where it will become 90 ignited through the opening n of the pilot-light or initial generator. When it is desired to extinguish the burner, the valve g² may be closed and the valve h⁹ left open, which will supply the initial generator with sufficient 95 heat to continue the generation of vapor or gas, thus providing a continuous flame for igniting the gas, when desired, from the burner. It is apparent that when the gas is ignited in the burner vapor will be quickly generated 100 in the frame B thereof. As the water circulates through the pipes E it is apparent that the steam will be quickly generated and that the bars D will be prevented from becoming overheated on account of the continuous flow 105 of water through the said pipes. In some instances I may omit the couplings e on the pipes E, and thus provide means for the circulation of air, which will also serve to prevent the bars D from becoming overheated, 110 thereby avoiding back-burning.

Having thus fully described my invention, what I claim as new, and desire to secure by Letters Patent, is—

1. In a hydrocarbon-burner, the combination with a box-like casing, of a series of bars located in parallelism at a slight distance apart in the upper portion thereof, pipes extending through said bars, a gas or vapor distributor located within the casing below the 115 bars and having a series of perforations, a generating-frame located on the upper portion of the casing and communicating with a source of oil-supply, substantially as described.

2. In a hydrocarbon-burner, the combination with a box-like casing, of a series of parallel bars located in its upper portion, pipes extending through said bars and casing and having their ends coupled together, one of 120 said pipes communicating with a supply of water and the other with a boiler, a generating-frame located on the upper part of the casing and having communication with an 125

oil-supply, and means to regulate the discharge of vapor or gas, substantially as described.

3. In a hydrocarbon-burner, the combination with a box-like casing, of a series of parallel bars located in its upper portion, pipes extending through said bars and casing and having their outer ends coupled together, one of said pipes communicating with a supply of water and the other with a boiler, a gas or vapor distributer located within the casing

below the bars and having a series of perforations, a generating-frame located on the upper part of the casing and having communication with an oil-supply, and means to regulate the discharge of vapor or gas, substantially as described. 15

STANISLAUS BERENS.
